L. COATALEN

VALVE OPERATING MECHANISM

Filed April 29, 1926

UNITED STATES PATENT OFFICE.

LOUIS COATALEN, OF WOLVERHAMPTON, ENGLAND.

VALVE-OPERATING MECHANISM.

Application filed April 29, 1926, Serial No. 105,519, and in Great Britain April 6, 1925.

This invention has for its object to provide improved means for effecting variable operation or control of a valve in a pump, internal combustion engine or other mechanism.

The invention comprises the actuation of the valve through a lever or levers which is or are operated by a pair of cams mounted on separate shafts, and the connection of the shafts by an epicyclic gear train which serves to transmit motion from one shaft to the other and also enables the angular relationship of the cams to be varied as required.

15 In the accompanying sheet of explanatory drawings:—

Figure 1 is a diagrammatic view showing one manner of carrying the invention into effect.

20 Figure 2 is a diagrammatic view of the means employed for varying the phase relationship of the cam shown in Figure 1.

In carrying the invention into effect as shown, a pair of shafts *a*, *b* arranged parallel with each other are each provided with a suitable cam *c*, *d*. Each shaft is provided with a gear wheel *e*, *f*. Motion is transmitted to *e* from a driving wheel *g*, and from *e* to *f* through other wheels *h*, *i*. The latter are carried on a movable system of links so that an epicyclic movement can be given to them. Preferably three links *j*, *k*, *l* are used. One (*j*) joins the shafts of the wheels *e*, *h*. Another (*k*) joins the shafts of the wheels *f*, *i*. The third (*l*) joins the links *j*, *k*. The link system is movable in any convenient manner. Preferably a sector *m* is secured to the link *j* and its toothed periphery is engaged by a worm *n* which can be rotated directly or indirectly by hand.

Motion is transmitted from the cams to the valve *o* by a three armed lever, or an equivalent pair of levers *p*, *q*. One end of the lever *q* is acted on by the cam *d*, and one end of the lever *p* by the other cam *c*. The other end of *q* engages the valve either directly or indirectly whilst the other end of *p* abuts on *q* through an adjustable screw *r*. Movement of the valve in the opposite direction is effected by a spring *s*.

With the mechanism as above described the angular or phase relationship between

the cams can be varied through the medium of the epicyclic wheels *h*, *i* (which otherwise serve to transmit motion from one cam shaft to the other) and consequently the duration of opening or closing of the valve can readily be varied between the limits for which the mechanism is designed.

The position in each cycle of operation at which the valve is opened can, and would usually, be fixed, the variation being made in the period for which the valve remains open. These conditions and others can, however, be varied to suit different requirements. Further the details of the mechanism can also be varied to suit the purpose for which the invention is required.

Having thus described my invention what I claim as new and desire to secure by Letters Patent is:—

1. In valve operating mechanisms, the combination of a valve operating lever, a pair of cams acting on said lever, means secured to one of said cams for rotating the other of said cams, whereby said cams rotate simultaneously, and means for angularly adjusting said cams relatively to each other.

2. In valve operating mechanisms, the combination comprising a valve operating lever, a pair of cams acting on the lever, epicyclic mechanism connecting said shafts for actuating the cams, and means whereby the said mechanism can be moved for effecting relative angular adjustment of the cams, substantially as described.

3. In valve operating mechanisms, the combination comprising a valve operating lever, a pair of non-coaxial cams acting on different parts of the lever, a pair of cam shafts, one for each cam, epicyclic mechanism connecting said shafts for actuating the cams, and means whereby the said mechanism can be moved for effecting relative angular adjustment of the cams, substantially as described.

4. In valve operating mechanisms, the combination comprising a valve actuating lever, a pair of non-coaxial cams acting on different parts of the levers, a gear wheel in driving connection with each cam, a pair of mutually engaging epicyclic wheels respectively engaging with the other gear

wheels, and means for imparting angular movement to the epicyclic wheels for effecting relative angular adjustment of the cams, substantially as described.

5. In valve operating mechanisms, the combination comprising a two-part valve actuating lever, a pair of non-coaxial cams acting on the two parts of the said lever, a pair of cam shafts, one for each cam, epi-

cyclic mechanism for actuating the cams, ¹⁰ and means whereby said mechanism connecting said shafts can be moved for effecting relative angular adjustment of the cams, substantially as described.

In testimony whereof I have signed my ¹⁵ name to this specification.

LOUIS COATALEN.
